F. W. MEYER,
GARMENT SUPPORTING FIXTURE,
APPLICATION FILED JUNE 8, 1912.

Patented May 6, 1913.

2 SHEETS—SHEET 2.

UNITED STATES PATENT OFFICE.

FRANK W. MEYER, OF OSHKOSH, WISCONSIN, ASSIGNOR TO THE OSHKOSH TRUNK COMPANY, OF OSHKOSH, WISCONSIN, A CORPORATION OF WISCONSIN.

GARMENT-SUPPORTING FIXTURE.

1,060,927.

Specification of Letters Patent.

Patented May 6, 1913.

Application filed June 8, 1912. Serial No. 702,382.

To all whom it may concern:

Be it known that I, FRANK W. MEYER, a citizen of the United States, and a resident of Oshkosh, in the county of Winnebago and State of Wisconsin, have invented certain new and useful Improvements in Garment-Supporting Fixtures; and I do hereby declare that the following is a full, clear, and exact description thereof, reference being had to the accompanying drawings, and to the letters of reference marked thereon, which form a part of this specification.

This invention relates to that class of garment supporting fixture having extensible or telescoping parts for supporting garments or hangers upon which garments are suspended.

The principal object of the invention is to provide a simple, economical and efficient garment supporting fixture adapted to be used in connection with trunks or cases and to enable garments to be supported within a compartment and to be readily withdrawn to more accessible position while supported by or suspended from such device.

Other and further objects of the invention will appear from an examination of the description and claims and from the accompanying drawings which are made a part of this specification.

The invention consists in features, combinations and details of construction herein described and claimed.

In the accompanying drawings:—Figure 1 is a perspective view of a trunk or case provided with a garment supporting fixture constructed in accordance with my improvements; Fig. 2 is a detail view in vertical section taken approximately on line 2—2 of Fig. 1 looking in the direction of the arrow, and showing the telescoping members of one side of the fixture in extended position; Fig. 3 is a similar view showing the members illustrated in Fig. 2 in collapsed position; Fig. 4 is a detail view in vertical section taken on line 4—4 of Fig. 2 looking in the direction of the arrow, and showing the tubular member and the manner of connecting the transverse and longitudinal frame portions of the slidable frame shown in Fig. 1; Fig. 5 is a detail view in vertical section taken on line 5—5 of Fig. 2 looking in the direction of the arrow, and showing an inner guiding bracket or catch; Fig. 6 is an

enlarged horizontal detail view partly in section showing a portion of the tubular member on one side of the slidable frame slidably mounted in a guiding member or bracket, a longitudinal side frame member slidably mounted in such tubular member, and a transverse frame member having connecting means extending through the slot in the tubular member and forming a connection between such transverse and longitudinal frame members; Fig. 7 is a view in horizontal section of a case or trunk provided with a garment supporting fixture constructed in accordance with my invention in a modified form. Fig. 8 is an enlarged horizontal detail view partly in section showing the arrangement and manner of connecting the longitudinal frame member and tubular members of the fixture shown in Fig. 7; Fig. 9 is an enlarged detail view in vertical section taken on line 9—9 of Fig. 7 looking in the direction of the arrow, and showing a tubular member slidably mounted in a guiding bracket or socket member secured to the case or compartment, and Fig. 10 is a similar detail view in vertical section taken on line 10—10 of Fig. 7 looking in the direction of the arrow, and showing a supporting bracket or guiding socket member, a tubular member slidably mounted in the bracket, and a longitudinal frame member slidably mounted in such tubular member and connected with a transverse frame member which extends through the socket in the tubular member.

In constructing a garment supporting fixture and mounting the same in operative position in a case, trunk or compartment, in accordance with my invention and improvements, I provide a case or trunk having a body portion comprising side walls *a*, end walls *b* and *c*, and a back or bottom wall *d*, and having a cover, lid or door *e* hinged to such body portion and adapted to form a closed compartment for containing clothes or garments to be suspended within such compartment. Secured to the upright or side walls of the case or compartment are supporting brackets or guiding socket members *f* which are held securely in rigid position by means of screws *g*. These stationary socket members or brackets are each provided with a guiding socket *h*.

A sliding frame is provided which is made preferably by bending a rod so as to form

longitudinal side frame members or portions *i* and an integral or transverse end frame member or portion *k*. Tubular members *l* having longitudinal peripheral slots *m* are 5 slidably mounted in the socket portions of the supporting brackets or socket members *f* on opposite sides of the slidable frame and with their slotted sides inward or toward the center of the frame. A transverse frame member *n* is secured at its opposite ends to the parallel side frame members or rod portions *i* by means of pins or rivets *o*; which pins or rivets may be in the form of or constitute end portions of said transverse member. 10 These transverse frame members or end portions, pins or rivets extend through the corresponding slot *m* in the adjacent tubular member so as to connect the longitudinal parallel side frame members or portions *i* in rigid relation to each other. The tubular members *l* are each provided at one 15 end with a collar or annular end portion *p* which encircles the corresponding side frame member or side rod *i* at points between the outer transverse end member *k* of the frame and the ends of the transverse member *n*. And the frame thus constructed may be provided with inner frame members *q* adapted to support clothes hangers *r* which may be 20 of any ordinary or desired form, but which are preferably of such construction as to comprise a top member having opposite slotted end portions *s* in engagement with hanger supporting members of the slidable 25 frame and a depending garment supporting member *t* adapted to enable garments to be suspended therefrom.

The transverse member which connects the parallel longitudinal side frame portions or 30 members of the slidable frame may be made in the form of a rod or bar *u*, shown in Fig. 7, having its opposite ends extending through the slots in the tubular members and secured to the longitudinal side frame 35 members *i* so as to form a rigid connection therebetween, as shown in Figs. 7 to 10 inclusive. When the device is constructed in the manner shown in Figs. 7 to 10 inclusive clothes hangers *v* may be mounted with 40 their slotted end portions *w* movably supported upon the frame members *u* and *k* respectively. Flexible guiding catches or yielding socket members *y* are mounted in the frame, case or compartment each in position to engage a tubular member *l* when the latter is moved inwardly to the position shown in Fig. 3, so as to prevent the accidental movement of the tubular members *l* outwardly or in a direction in which they 45 are moved in order to form a support for the slidable frame when the latter is in its extended or outermost position. An enlarged end portion or collar *z* is mounted upon the end of each of the tubular members *l*, as shown in Fig. 2, each of which

forms an annular shoulder adapted to engage a guiding socket member or bracket *f*, in such a manner as to limit the outward movement of the tubular members.

The transverse frame members or connecting pins *o* which extend through the slots *m* are adapted to pass through the sockets *h* and to engage the ends of the corresponding slots *m* in the tubular members, so as to limit the outward movement of the 75 slidable frame when it reaches the position indicated in Figs. 1 and 2.

In order to render the slidable frame as rigid as possible consistent with the weight of the material used in this construction, 80 and in order that such frame may be so constructed as to occupy as small a space as possible in the case, trunk or other compartment in which it is mounted, the transverse member *n* is of such construction that when 85 lying in a horizontal plane or in the plane of the frame of which it forms a part, as shown in Figs. 1 and 2, its widest surfaces will be in a plane perpendicular to the plane of the longitudinal side frame members *i*. The end portions 2 of the transverse member *n* are bent into such a position that they are parallel with the side frame members *i* and so disposed as to provide a space between the end portions 2 and 90 the side frame members *i* adapted to enable the slidable frame to move freely with respect to the tubular members and to admit the longitudinal slotted portions of the tubular members between the end portions 2 95 and the side frame portions *i*. By providing a plurality of connecting and guiding pins or transverse frame members *o* and securing their opposite ends to the end portions 2 of the transverse frame member *n* 100 and to the longitudinal rods or frame portions *i*, as shown in Figs. 1 and 2, the ends of the frame portions *i* are so connected that the frame is for all practical purposes as strong and rigid as if it were made of one 110 integral piece. The inner braces or frame members *q* serve to still further strengthen and increase the rigidity of the frame as well as to provide suitable means for supporting the removable hangers thereon, as 115 already suggested.

By the above arrangement it will be readily seen that a slidable frame is provided which is of rigid construction adapted to afford the maximum strength consistent 120 with the weight of the material of which it is formed, and that, being of rigid construction, it may be readily moved inward and outward or from extended to collapsed position or vice versa with the clothes or 125 garments suspended upon suitable hangers which are removably mounted thereon, and that the fixture when in extended position will form a strong and efficient support for the garments, and is adapted to be operated 130

with great facility, and has the advantage of great durability and simplicity of construction.

I claim:

- 5 1. In an extensible supporting device, the combination of two endwise movable tubular members, provided with inwardly and oppositely facing, longitudinal slots, guide brackets for supporting said tubular members, located inwardly from the ends of the paths of movement thereof, and provided with slots coinciding with those of the tubular members, rods slidably mounted in said tubular members, and horizontal transverse members extending between and rigidly connecting the extremities of said rods; said transverse members being located in the same horizontal plane with said rods and one of said transverse members having its 26 end portions extended horizontally through the slots of said tubular members and attached to the said rods inside of the same.
2. In an extensible supporting device, the combination of two endwise movable tubular members, provided with inwardly and oppositely facing slots extending substantially

the entire length thereof, guide brackets supporting and limiting the movement of said tubular members, and provided with transverse slots corresponding to the slots 30 of said tubular members, and a slideable frame member comprising a rectangularly bent U-shaped rod, having its parallel side portions slidably mounted in said tubular members, and a horizontal, transverse bar 35 member provided with end portions bent at right angles thereto, said transverse bar member extending between the extremities of the parallel side portions of said rod, and provided with pins extending through the 40 slots of said tubular members and rigidly secured in the end portions of said transverse bar member and of the rod.

In testimony, that I claim the foregoing as my invention I affix my signature in the 45 presence of two witnesses, this fifth day of June A. D. 1912.

FRANK W. MEYER.
